HAND TOOL

Filed Dec. 17, 1927

Inventor:
Fayette Nims
By Frank M. Slough
his attorney.

UNITED STATES PATENT OFFICE

FAYETTE NIMS, OF MONTOUR FALLS, NEW YORK

HAND TOOL

Application filed December 17, 1927. Serial No. 240,672.

My invention relates to hand tools and relates particularly to hand tools such as hand trowels and the like which have a metallic blade of the spade type formed integrally with a tubular handle for the blade.

In hand tools of this general type, moisture is received within the tubular handle made commonly of steel and which is integrally formed from a single sheet of sheet metal, with the working blade of the tool, causing rusting of the interior surface of the handle and moreover the condition of moisture is maintained for a considerable period by particles of soil which are received within the handle.

The soil received within the tubular handle through the opening usually provided at the small end of the handle adjacent the blade which is open on the back side of the tool, remains in the tool until at some later time it may subsequently drop out in a tool box or the interior of buildings where it is undesirable to have deposited such particles of soil.

An object of my invention, therefore, relates to a provision in a hand tool of the class described or a tubular handle therefor, formed integrally with the blade and which will be substantially closed at its ends, and particularly at its end adjacent the blade of the tool.

Another object of my invention is to effect the closure of the handle against the ingress of extraneous substances by means formed integrally with the handle and blade in a single piece and without any substantial additional expense of manufacturing the tool.

Other objects of my invention and the invention itself will become apparent by reference to the following description of an embodiment of my invention and in which description reference will be had to the accompanying drawing illustrating the said embodiment.

Referring to the drawing:

Fig. 1 shows a plan view of a trowel embodying the principles of my invention.

Fig. 2 is a side elevation thereof.

Fig. 3 is a plan view of a blank of sheet metal from which the trowel is formed by suitable bending and forming operations.

Fig. 4 is a transverse section taken on the line 4—4 of Fig. 1.

Fig. 5 is a longitudinal medial sectional view taken on the line 5—5 of Fig. 2.

Fig. 6 is a plan view taken from the rear of the trowel.

Referring now to the different figures of the drawing, at 1 I show a sheet metal trowel blade, of the spade type, which takes the form illustrated in Figs. 1, 2 and 6, after a suitable forming operation performed upon the portion 1' of the blank illustrated in Fig. 3. At 2 is shown the tubular handle of truncated conical form from the line of section 4—4 of Fig. 1 toward the butt end which is preferably made of rounded form to close the larger end of the handle. A pair of complementary rounded closure portions 3 formed from the flaps 3' of the blank of Fig. 3, have abutting edges 13 which are continuous with the abutting edges 23, forming the seam 23' of the handle at its rear side.

At 4 and 14 I show arcuate slits extending inwardly into the blank from the rear edges 5 and 15, respectively, of the tool blade, whereby the flaps 6 and 16 are provided on opposite lateral sides of the blank contiguous to the rear edges 5 and 15, respectively, of such a form, that they may be infolded as illustrated in Figs. 4, 5 and 6 in overlapping relation as best illustrated at 7, and with their arcuate edges 4' and 14' for the flaps 6 and 16 respectively, disposed contiguously and preferably in engagement with the rounded concave surface 8 of the formed rear side of the tool at and adjacent the junctions of blade and handle and which surfaces merge into the interior surface of the tubular handle.

It will be seen, therefore, that I have provided a tapered tubular handle 2 closed at both ends by an integral substantial dome-shaped closure at the butt end, comprising the formed flaps 3' and at the small end closed by the infold flaps 6 and 16.

In forming the flaps 3' it is necessary to stretch the intermediate portions at least of each of the flaps so as to make each flap substantially into the form of a character of a hollow sphere, and then when the tubular handle 2 is given the proper tapered form

wherein its intermediate portions are of generally the form of a hollow truncated cone, the arcuate edges of the flaps 3' will come together or substantially so so that little or no space is left between the edges to permit extraneous substances to enter the handle from its butt end. This rounded end of the handle is very much to be desired since in operating the tool the palm of the hand may be thrust 10 against this rounded end with a minimum of discomfort to the operator and transmitting the thrust to the blade in a very efficient manner.

The infolded flaps 6 and 16 make a closure 15 of the small end of the handle and in addition reinforce the handle in its smallest, weakest portion, namely, close to the line of section 4—4 of Fig. 1, since the edges 4' and 14' are adapted to and do engage the inner surface 20 of the neck 9 which is smaller and contains less metal and is weaker than any other part of the trowel subjected to lateral stresses.

In finishing the trowel, I preferably paint 25 the handle, at least so that the paint flowing over the contiguous edges 13 of the butt end flaps 3 and the contiguous portions of the flaps 6 and 16 and the edges 4' and 14' contiguous with the rounded surface 8, improving the closure at these points to the 30 ingress of extraneous substances.

Having thus described my invention as a preferred embodiment, I am aware that numerous and extensive departures may be 35 made from the embodiment herein illustrated and described without departing from the spirit of my invention.

I claim:

1. In a hand tool, a blade and handle, said 40 handle being of tapered tubular form with a longitudinal seam on one of its sides, said blade being integrally formed of sheet metal, the blade comprising an integral enlarged extension of the smaller end of the handle, said 45 handle comprising a pair of end flaps formed integrally therewith and inturned against its interior surface adjacent the junction of the handle and the blade, to form a substantial 50 closure of the tubular handle at its smaller end.

2. In a hand tool, a blade and handle, said handle being of tapered tubular form with a longitudinal seam on one of its sides, said blade being integrally formed of sheet metal, the blade comprising an integral enlarged extension of the smaller end of the handle, said handle comprising a pair of end flaps formed integrally therewith and inturned against its 55 interior surface adjacent the junction of the handle and the blade, to form a substantial closure of the tubular handle at its smaller end, said handle at its larger end comprising integral inturned end flaps having the 60 combined form of a rounded dome and

adapted to take the thrust of an operator's hand in the operation of the tool.

In testimony whereof I hereunto affix my signature this 7th day of December, 1927.

FAYETTE NIMS.
